REPORT FOR THE DISTILLATION OF COAL

Harold Stevens, Cincinnati, Ohio, assignor, by
mesne assignments, to Harold Stevens, trustee

Application October 18, 1930. Serial No. 489,534

3 Claims. (Cl. 202—99)

This invention relates to improvements in starting resistors such as are used in the distilling of coal as described in my copending application Serial No. 489,535, filed October 18, 1930.

In that process of distilling coal a charge of coal is introduced into a retort with an electrical resistor means embedded in the charge and connected so that current may be passed therethrough. In operation the resistor becomes heated by its resistance to the passage of current therethrough and the coal is heated progressively outward from the point of application of the heat. As the coal cokes the coked portions act as additional resistor means.

It is one of the primary objects of the present invention to provide a simple and effective starting resistor.

I accomplish the foregoing by means of a construction which I have illustrated in the preferred form, wherein—

Fig. 1 is a vertical section through a retort with my improved resistor in place.

Fig. 2 is an enlarged view partially in section showing the construction of the resistor.

Fig. 3 is a section taken on the line 3—3 of Fig. 2, of a modification of the resistor.

Fig. 4 is a sectional view illustrating a modification of the invention.

This application is in part a continuation of my application Serial No. 686,053, filed January 14, 1924.

Referring now to Figs. 1 to 3 inclusive, the reference numeral 7 indicates the retort which may be of any suitable construction such as described in my copending application Serial No. 489,535 referred to above wherein a removable closure member 7a (see Figure 1 herein) serves to permit downward discharge after treatment of the coal. The reference numeral 8 indicates the starting fuse or resistor and the reference numerals 9 and 10 the electrodes therefor. The electrode 10 is preferably made of the construction illustrated, described and claimed in my copending application Serial No. 489,532, filed October 18, 1930.

The resistor 8 is composed of a tube 8a which may be composed of paper or metal, preferably the latter, and which is filled with coke 11 or other suitable material. The tube is preferably corrugated as indicated at 12 in Fig. 3 for purposes of lightness and strength.

The fuse is introduced through the electrode 10 and the tube 8a may be left in place or removed through the electrode after the retort has

been charged, as may be desired. In this connection the coke within the tube is preferably sufficiently coarse as to be retained in position by the charge even on withdrawal of the tube 8a. When the tube is withdrawn prior to treatment, 60 the coke of the resistor device, of course, is removed with the charge after treatment thereof. If desired, the tube 8a may be made of tin, bismuth, cadmium or other material functioning as a catalyst, in which case the tube is left in 65 position. The tin, bismuth or cadmium is coated on the tube or alloyed with other metals to constitute the tube. These catalysts apparently function to alter the tarry acids produced in distillation into substantially neutral compounds. 70 Other catalysts may be used for other purposes.

In Fig. 4 the electrodes 9a and 10a are spring held and are entered into the ends of the tube 12. In operation, in case of shrinkage of the starting core of coke or of shrinkage or slight 75 settling of the charge, the springs operate to advance the electrodes, thereby maintaining proper contact and thus maintaining a path for the current.

In the arrangement of Fig. 1, instead of having the electrodes spring held as in Fig. 4, the upper electrode has a gravity feed for the purpose of maintaining contact. To this end it slidably fits in the stuffing box 13, and the supporting cable is slackened off after charging. 80

Attention is called to the fact that various features herein disclosed are described and claimed in one or more of the following of my copending applications: Serial No. 489,530, filed October 18, 1930; Serial No. 489,532, filed October 18, 1930; Serial No. 489,535, filed October 18, 1930; and Serial No. 489,536, filed October 18, 1930. 90

I claim:—

1. In a retort for distilling solid carbonizable materials, an electrode at the bottom of the retort, an electrode at the top of the retort, said electrodes being substantially centrally located in the retort and the upper electrode being hollow, and a resistor device insertible and removable through said hollow electrode, the resistor device including a metallic tubular part of length sufficient to complete a current path between the electrodes, and separate particles of coke filling said tube. 100

2. In a retort for distilling solid carbonizable materials, an electrode at the bottom of the retort, an electrode at the top of the retort, said electrodes being substantially centrally located in the retort and the upper electrode being hol- 110

low, and a resistor device insertible and removable through said hollow electrode, the resistor device being adapted to complete a current path between the electrodes and including discrete coke-like particles, and a form retaining shell adapted to position said particles in electrically conducting relation during charging of the retort, the upper electrode and said shell being arranged so as to effect withdrawal of the latter through said hollow electrode when the charging has been completed.

3. In a retort for distilling solid carbonizable materials, an electrode at the bottom of the retort, an apertured electrode at the top of the retort projecting downwardly into the retort for a substantial distance, and a resistor device in-

sertible and removable into the retort through said apertured electrode, the resistor device being adapted to complete a current path between the electrodes and including discrete coke-like particles, and a form retaining shell adapted to position said particles in electrically conducting relation during charging of the retort, the resistor device being of sufficient length to span the distance between said electrodes and to extend into the aperture of the upper electrode for a substantial distance, and the upper electrode and said shell being arranged so as to effect withdrawal of the latter through said aperture when the charging has been completed.
